UNITED STATES PATENT OFFICE.

OBADIAH Y. MOSER AND JACOB W. DORNSEIF, OF WORDEN, ILLINOIS.

HAT-FASTENER.

SPECIFICATION forming part of Letters Patent No. 625,587, dated May 23, 1899.

Application filed March 20, 1899. Serial No. 709,825. (No model.)

To all whom it may concern:

Be it known that we, OBADIAH Y. MOSER and JACOB W. DORNSEIF, of the city of Worden, Madison county, State of Illinois, have 5 invented certain new and useful Improvements in Hat-Fasteners, of which the following is a full, clear, and exact description, reference being had to the accompanying drawings, forming a part hereof.

10 Our invention relates to hat-fasteners; and it consists of the novel construction, combination, and arrangement of parts hereinafter described and claimed.

Figure 1 is a perspective view of a hat with 15 a part of the crown broken away, showing our improved invention in position. Fig. 2 is a bottom plan view of our invention, showing the coiled wire spring partly out of the casing. Fig. 3 is plan view of the same with 20 the under casing removed, showing the construction of the spring. Fig. 4 is a vertical sectional view taken on the line *a a* of Fig. 2. Fig. 5 is a perspective view of a portion of the inner casing, showing the wire in position ready to be passed through its slot.

25 The object of the invention is to construct a device that may be fastened to the top of the crown of a hat and is designed to be operated from the outer portion of the hat in order to have its wire spring come in communication with the hair of a person, thus holding the hat tightly thereon, and to take the place of the ordinary hat-pin which is now in use.

30 Referring to the drawings, 1 indicates our complete invention, which consists of an outer casing 2 of any desirable width and depth and is provided on two sides with ears 3, in which are formed elongated openings 4, through 35 which are passed fasteners or screws, whereby the same is held to the crown of the hat. Within the casing 2 is placed a casing 5 and is held therein by tongues 6, formed on the edge of the vertical portion of the casing 2, and are bent inwardly a sufficient distance 40 to bind against the under surface of the casing 5, thus holding the same in a rigid position. In the casing 5 is provided a slit 7, the one-half of the casing opposite the slit being 45 bent inwardly, as shown in Figs. 4 and 5, which is for the purpose of allowing the coil-

55 spring 8 to pass therethrough and coil on the outside of said casing. The coil wire spring 8 is secured to a post 9, which is passed through an opening 10, formed in the upper portion of the outer casing 2, and is constructed to pass also through the material of the hat, as shown in Fig. 1, and is provided at its top with a knob 11, which is suitably held thereto in any desirable manner and by 60 which the post and spring are turned and operated. The spiral spring 8 may be of any desired length, according to the depth of the crown of the hat in which it is to be used. In extending the spring for this depth the 65 same may be pulled apart sufficiently by which to allow the end as it passes through the slit 7 in the inner casing to have a more downward angle, and in this manner it is not necessary to construct the spring of more material than is at present contained in the device. 70

The invention may be secured in the crown of a hat in other ways than by a fastener or screw. This of course is done according to 75 the desire of the user.

This invention is used in hats worn by women, and when the same is operated the end of the spiral passes through the hair sufficiently, thus bearing down upon the crown 80 of the hat and binding the same upon the head of the wearer.

The operation of the invention is as follows: After the device is placed within the crown of the hat and it is desired to operate the same 85 the knob 11 is turned, which operates the spiral, bringing its end 12 in communication with the slit 7 and passing therethrough on the outer under side of the inner casing 5, thus allowing as much of the spiral to pass 90 therethrough as desired, according to the depth of the crown. By the continual turning of the knob 11 the end of the spiral 12 after passing through the slit in the casing comes in contact with the hair and winds 95 therethrough, which then pulls downward upon the device and also the top of the crown, holding the same tightly to the head, thus preventing the hat from being displaced. In releasing the device from the head the knob 100 is again turned in a direction opposite to that in which the device was applied. Thus the

spiral is released from the hair and brought back into the casing, as shown in Fig. 4, entirely out of view.

We claim—

- 5 1. In a hat-fastener, having an outer and inner casing, an opening formed in the bottom of the inner casing, said casings suitably held together and provided with a means by which the same is held in a hat, a spiral housed in said casing and secured to a post, said post passing through the outer casing and hat and provided with a knob, said spiral operated by said knob and passed through the opening and engaging with the hair of 15 the wearer; substantially as specified.
- 15 2. A hat-fastener, having a casing composed of three members held together, an opening

formed in the lower member, and ears on the outer member, a spiral housed in said casing, its one end secured to a post which is passed 20 through the top of the outer casing and the hat, a knob secured to said spiral for operating the same, said spiral adapted to pass through the opening in the under casing and wind through the hair of the wearer for the 25 purpose of retaining the hat upon the head, substantially as specified.

In testimony whereof we affix our signatures in presence of two witnesses.

OBADIAH Y. MOSER.
JACOB W. DORNSEIF.
